US0D1070845S

(12) **United States Design Patent** (10) **Patent No.:** **US D1,070,845 S**
(45) **Date of Patent:** **** Apr. 15, 2025**

(54) **COMPUTER**

(71) **Applicant:** **Apple Inc.**, Cupertino, CA (US)

(72) **Inventors:** **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Ismael Basso**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Alexandre B. Girard**, Sunnyvale, CA (US); **Jonathan Gomez Garcia**, San Francisco, CA (US); **M. Evans Hankey**, San Francisco, CA (US); **Anna Heck**, San Francisco, CA (US); **Moises Hernandez Hernandez**, Palo Alto, CA (US); **Richard P. Howarth**, San Francisco, CA (US); **Julian Jaede**, San Francisco, CA (US); **Duncan Robert Kerr**, San Francisco, CA (US); **Kainoa Kwon-Perez**, San Francisco, CA (US); **Nicolas Pedro Llyyk**, Los Gatos, CA (US); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Eugene Antony Whang**, San Francisco, CA (US)

(73) **Assignee:** **Apple Inc.**, Cupertino, CA (US)

(**) **Term:** **15 Years**

(21) **Appl. No.:** **29/827,163**

(22) **Filed:** **Feb. 17, 2022**

(51) **LOC (15) Cl.** **14-02**

(57) **CLAIM**

The ornamental design for a computer as shown and described.

DESCRIPTION

FIG. 1 is a perspective view of a computer showing the claimed design;

FIG. 2 is another perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
 FIG. 8 is a bottom view thereof.
 The broken lines illustrate portions of the computer which
 form no part of the claimed design.

1 Claim, 8 Drawing Sheets
